UNITED STATES PATENT OFFICE.

STANLEY PYTLAK, OF McMECHEN, WEST VIRGINIA.

WALL-PAPERING DEVICE.

Application filed May 13, 1922. Serial No. 560,582.

To all whom it may concern:

Be it known that I, STANLEY PYTLAK, a subject of Poland, and resident of McMechen, county of Marshall, and State of West Virginia, have invented certain new and useful Improvements in Wall-Papering Devices, of which the following is a specification.

This invention relates broadly to wall papering devices, and it has for its primary object to provide mechanism whereby a roll of wall paper is supported during the operation of applying lengths thereof to a wall and whereby adhesive paste is automatically applied to such paper as the latter is paid out for application to the wall.

A further object is to simplify, structurally improve and render more efficient and practical the wall-papering machine disclosed in my prior Patent No. 1,395,519, granted November 1, 1921.

With these and other objects in view, the invention resides in the features of construction, arrangement of parts, and combinations of elements which will hereinafter be fully described, reference being had to the accompanying drawings, in which—

Figure 1 is a front elevation of a wall-papering device constructed in accordance with my invention;

Figure 2 is an end elevation of the same;

Figure 3 is a fragmentary detail view showing in top plan the hinged paste container swung to open position and showing the paper-roll container in longitudinal section;

Figure 4 is a transverse section on line 4—4, Fig. 3;

Figure 5 is a sectional elevation on line 5—5, Fig. 2;

Figure 6 is a side elevation of the roll-carrying roller, detached;

Figure 7 is an inner face view of the detachable cap for the roll container; and—

Figure 8 is an edge view of the same.

Referring to said drawings, 1 indicates a hollow cylinder having one end 1^a closed and carrying a removable cap 2 at its opposite end. A partition 3 is fixed in said cylinder adjacent to said end 1^a, thereby forming an intermediate narrow compartment 4 in which is disposed a gear wheel 5 having a hub 6 with its opposite end journaled in bearings 7 and 8 formed centrally on said end 1^a and said partition 3, respectively. Said hub 6 has a square hole extending axi-

ally therethrough, the same being adapted for the reception of a squared stem 9 formed on an end of a roller 10 which is designed to have a roll of wall paper wound thereon, a longitudinal slit 11 being provided in said roller for the reception of the inner end of said roll. The detachable cap 2 has a bearing 12 formed centrally thereof for the reception of the spindle 13 carried by the opposite end of said roller.

Attached to said cylinder 1 by a hinge or hinges 14 is a casing 15 which is divided longitudinally by a partition wall 16 into two compartments 17 and 18, the former having journaled therein a cylindrical brush 19 designed for applying adhesive paste to the paper as the latter is unwound from the roller 10.

Formed in the front wall of the cylinder 1 is a narrow longitudinal opening or slot 60 through which the paper 61 is drawn as it is unwound from said roller 10. Carried by, or formed integral with said cylinder is a plain flat forwardly-directed flange 20 which, when the cylinder and the hinged casing 15 are in normal relation, rests upon and serves as a cover-plate for the open top of the brush compartment 17. The extreme outer edge of said flange 20 is inclined upward, as shown at 20^a. As the paper is drawn outward for application to a wall, it is guided by said flange 20 in a path in which it is directly contacted by the revolving brush 19. Emerging beneath the front edge of said flange 20, the free end of the paper roll extends to and under a rod or roller 22, thence vertically upward in front of a rotary brush 23 which is adapted to bear upon the paper and press it to the wall.

The compartment 18 is designed as a container for paste which is supplied gradually to the compartment 17 through suitable openings or perforations 24 so that it may, as needed, be taken up by the brush 19 and applied to the paper as the latter passes in contact with said brush.

When the parts of the structure occupy normal positions, a small idle gear or pinion 105 suitably journaled within an end of the compartment 17 and which projects through registering slots 26 and 27 in said compartment and the cylinder 1 is disposed in operative relation to the gear 5. Said pinion is permanently in mesh with a gear wheel 28 carried by the adjacent trunnion 29 of said brush

19. Therefore, as is manifest, rotation of the roller 10 effected through withdrawal of paper from the roll carried by said roller is communicated through the gear 5, pinion 25 5 and gear 28 to said brush 19 for applying paste to said paper.

A gear wheel 30 carried by the opposite spindle or trunnion of the brush 19 is adapted, when the hinged casing occupies its 10 working position, to operatively engage a pinion 31 carried by an end of a short shaft 32 which is journaled in lugs 33 carried by the flange 20. Fixed on said shaft 30 is a small disk 34 having a peripheral cutting edge. Said disk projects through an opening 35 in said flange 20 and is designed to trim the waste margin from the paper which is drawn outward beneath said flange in applying the paper to the wall. As is manifest, 15 rapid rotary motion is communicated to the shaft 32 which carries said trimming disk 34 through the paste-applying brush 19 and the intermeshing gears 30 and 31.

The paper applying brush 23 is rotatably 20 mounted adjacent its opposite ends in the side members 36 of a frame which is rigidly carried by and extends forward from the cylinder 1, said members being rigidly connected by a cross member or bar 37. Braces 30 38 are interposed between the cross-bar 37 and the inclined edge 20^a of the flange 20, whereby the latter is firmly supported. Brackets 39 depending from the frame members 36 have the rod or roller 22 journaled 35 thereon.

Fixed to the casing 15 is a pair of runner members 40 designed to bear against the wall in advance of the paper strip which is being applied, for maintaining the apparatus 40 in proper position relative to the wall.

Access to the paste-reservoir, as for introducing a supply of paste is had through an opening in the flat top of said reservoir, said opening being normally maintained 45 closed by a suitable close-fitting slide 42.

The hinged casing 15 is normally supported in its proper relation to the cylinder 1 by means of upright pins 43 which are disposed for rotary movement in brackets 44 50 carried by the opposite ends of said casing. Laterally extending lips 45 formed on or carried by the flange 20 have slots 46 therein through which oblong heads 43^a formed on said pins may freely pass when disposed in 55 one position and which are crossed by said heads when the latter are in another position.

Wheels or disks 47 are fixed upon the opposite ends of the shaft of the brush 23, the 60 same being designed to impart rotation to said brush through frictional contact with the wall as the apparatus is moved downwardly in engagement with said wall.

Pins 48 carried by the cylinder 1 are 65 adapted to cooperate with the cap 2 for de-

tachably securing the latter in place, bayonet slots 49 provided in said cap being designed to receive said pins.

What is claimed is—

1. A wall papering apparatus comprising 70 a holder for a roll of paper, a casing having hinged connection with said holder, said casing being divided longitudinally to form a brush compartment and a paste reservoir and having passages permitting paste to 75 pass from said reservoir to said compartment, a rotary paste-applying brush in said compartment, said compartment being open at its top, paper guiding means holding the paper to said brush as it is drawn from said 80 holder across said open top, and a rotary cutting disk whereby a marginal edge is trimmed from the paper as it is drawn from said holder.

2. A wall papering device comprising a 85 paper-roll container having a longitudinal slot therein, a flat flange carried by said container adjacent to said slot, a casing hinged to said container and divided into a paste reservoir and a brush compartment 90 with passages for feeding paste from the former to the latter, said compartment being open at its top, a rotary paste applying brush in said compartment, said casing being adapted to assume a position in which 95 said flange closely overlies said opening for holding to said brush the paper as it is withdrawn through said slot, and means for detachably securing said casing in said position.

3. A wall papering device comprising a paper-roll container having a longitudinal slot therein, a flat flange carried by said container adjacent to said slot, a casing hinged to said container and divided into a paste 105 reservoir and a brush compartment with passages for feeding paste from the former to the latter, said compartment being open at its top, a rotary paste applying brush in said compartment, and means for detaching 110 said casing to said flange in a position in which the latter closely overlies said opening.

4. A wall papering device comprising a paper-roll container having a longitudinal 115 slot therein, a flat flange carried by said container adjacent to said slot, a casing hinged to said container and divided into a paste reservoir and a brush compartment with 120 passages for feeding paste from the former to the latter, said compartment being open at its top, a rotary paste applying brush in said compartment, means for detachably securing said casing to said flange in a position in which the latter closely overlies said opening, and a rotary edge trimmer carried 125 by said flange.

5. A wall papering device comprising a paper-roll container having a longitudinal slot therein, a flat flange carried by said con- 130

tainer adjacent to said slot, a casing hinged to said container and divided into a paste reservoir and a brush compartment with passages for feeding paste from the former 5 to the latter, said compartment being open at its top, a rotary paste applying brush in said compartment, means for detachably securing said casing to said flange in a position in which the latter closely overlies 10 said opening, a rotary edge trimmer carried

by said flange, and gearing whereby said trimmer is positively driven.

In testimony whereof, I affix my signature in presence of two subscribing witnesses.

STANLEY PYTLAK.
